UNITED STATES PATENT OFFICE.

HARRY A. DAVIS, OF HOPEDALE, MASSACHUSETTS, ASSIGNOR TO DRAPER CORPORATION, OF HOPEDALE, MASSACHUSETTS, A CORPORATION OF MAINE.

FEELER MECHANISM FOR LOOMS.

Application filed April 25, 1924. Serial No. 708,907.

To all whom it may concern:

Be it known that I, HARRY A. DAVIS, a citizen of the United States, and a resident of Hopedale, in the county of Worcester 5 and State of Massachusetts, have invented an improvement in feeler mechanisms for looms, of which the following description, in connection with the accompanying drawings, is a specification, like characters on 10 the drawings representing like parts.

This invention relates to feeler mechanisms for looms whereby the operative condition of the loom is changed from time to time, as, for instance, replenishment of 15 filling.

Feeler looms equipped with intermittent feeler mechanisms provide that the feeler of said mechanisms shall have periods of activity and periods of inactivity during 20 weaving with the same supply of filling in the shuttle, so that the recurring contact of the filling by the feeler is avoided for the most part. Since the character of the filling in the shuttle may be changed from 25 time to time in the production of different characters or kinds of cloth, it becomes desirable to provide in the intermittent feeler mechanism a condition that will permit the active periods of the feeler to be varied 30 in their duration and in accordance with the character of the filling employed. One of the objects of the present invention, therefore, is to provide a feeler mechanism of the intermittent type wherein provision is made 35 for enabling the active periods of the feeler to be varied in their duration in order that the feeler may properly function in connection with the different kinds and characters of the filling that may be employed; and 40 another feature of the present invention consists in means for readily varying both the periods of activity and inactivity of the feeler.

When weaving with fine filling, the time 45 required for the depletion of the filling to a predetermined point is greater than when weaving with filling of a coarser kind, consequently when weaving with fine filling it is not necessary that the feeler shall be released to its periods of activity as frequently as when weaving with coarser filling or filling which is more rapidly depleted from the filling carrier. The present invention

therefore provides a feeler mechanism of the intermittent type which may be readily 55 adapted for the weaving of various kinds of filling in the same loom.

The invention and new combination of parts will best be made clear from the following description and the accompanying 60 drawings of one good form thereof, it being understood that the invention is not necessarily restricted to the details, which may be changed.

In the drawings: 65
Fig. 1 is a perspective view of the portions of a loom at the feeler side thereof, showing the present invention associated therewith;

Fig. 2 is a side elevation of the feeler mechanism embodying the present invention; 70

Fig. 3 is a section on the line 3—3 of Fig. 2; and

Fig. 4 is a plan view. 75

The loom frame 1 has mounted thereon the transverse shaft 2 which may be appropriately supported in bearing brackets 3, one of which is secured to each side of the loom. Secured to the shaft 2 and extending upwardly therefrom is an arm 4 to which is pivoted at 5 the rearwardly extending member 6 having pivotally associated therewith, as at 7, a rearwardly extending arm 8 which is adapted from time to time to be engaged by the operating member 9 which may be appropriately formed as a part of or connected to the cam follower. 80

The arm 8 has secured thereto a finger 10, in the present instance which overlies one arm 11 of a bell crank pivoted at 12 to a support 13 connected to the loom frame. The other arm 14 of the bell crank is connected to a transmitter 15. 85

Adjustably mounted on the loom frame is the feeler stand 16 which may be adjustably connected to the loom frame by a slot 17 through which passes a bolt 18. 90

At the rear portion of the feeler stand 16 is the bearing 19 in which is mounted the slide 20 connected at 21 to the transmitter 15. 100

The feeler 22 passes through an opening in the slide 20 and its frontwardly extending stem portion 23 passes through a swivel 105

block 24 mounted in a bracket 25 connected to the feeler stand, and interposed between the swivel block 24 and the support or bridge 26 secured to the feeler is a spring 27 normally tending to move the feeler to its rearward feeling position. A cap plate 28 is mounted on the rear bearing 19 and forms a convenient means for confining the slide 20 in its guideway, and through an opening in the slide 20 the feeler 22 extends. The construction thus far described may be substantially as that shown and described in the patent to Edward S. Stimpson, Serial No. 1,309,226, dated July 8, 1919.

15 The present invention is shown as associated with a feeler of the inclined type but it is to be understood that the invention is not restricted thereto but may be advantageously employed in connection with 20 any usual type of feeler which will function to call the change or replenishment of filling when the filling in the shuttle has become substantially exhausted.

It has not been deemed necessary herein 25 to show and describe the mechanism for replenishing the filling, since such mechanism is now well understood, and the details thereof form no essential part of the present invention.

30 The lay 29 is provided with the usual shuttle box 30 having an opening 31 in its front wall with which registers the opening 32 in the wall of the shuttle 33 when the latter is in the box at the feeler side of 35 the loom. The shuttle 33 carries the usual filling carrier or bobbin 34 on which the filling 35 is wound.

At the side of the feeler stand, as shown, 40 is a feeler withdrawing device or detent which is adapted to withdraw the feeler frontwardly beyond the reach of the filling on detecting beats when the feeler is in its inoperative or inactive position. In the present instance, the feeler stand has extending 45 downwardly therefrom the bracket 36 on which is pivotally mounted at 37 a rocker arm 38, the upper end portion of which is connected at 39 to the detent 40.

The toothed end portion of the detent 40 50 may be variously contrived, but in the present instance the engaging end 41 of the detent is formed separately from the detent itself and has a threaded stem 42 which passes through lugs 43, 44 of the detent, 55 and between such lugs there is a thumb nut 45 whereby the active end 41 of the detent may be adjusted into cooperative relation with a part carried by the feeler for withdrawing the feeler to a frontward position. In the present instance, the collar or bridge 26 of the feeler has a side portion 46 formed as an inclined tooth, the rear edge portion of which is adapted to engage 60 a tooth formed on the active end of the 65 detent when the feeler is moved frontwardly

by a working supply of filling on a detecting beat.

The active end 41 of the detent is provided with two teeth 47, 48, either one of which may, under certain conditions, be engaged by the part 46 carried by the feeler. When the filling opposite the feeler is being withdrawn from the filling carrier or bobbin, the feeler may not be moved frontwardly so far as when the filling is being withdrawn from near the end of the bobbin, and in such cases the feeler will be not be moved frontwardly so far as to engage the front tooth 48 of the detent but will engage the tooth 47. In either case, however, the detent when engaged with the feeler will be actuated to move the feeler to a position beyond the reach of the filling on detecting beats.

Mounted on the bracket 36 extending 85 from the feeler stand is a stud or dead shaft 49 on which is mounted the toothed wheel or ratchet 50, the teeth of which are adapted to be engaged by a pawl 51 carried by a rocking arm 52 which may be conveniently 90 mounted for rocking movement on the stud or dead shaft 49. The end portion 53 of the arm 52 is provided with a slot 54.

Mounted on the stud 49* at one side of the dead shaft is the arm 55 which is likewise provided with a slot 56, and between the two arms and passing through the slots 54 and 56 thereof is an adjustable connector 57 which is shown in the present instance as a threaded bolt which may be clamped in 100 position in the slots of the arms by means of nuts or other equivalent means 58, the construction being such that should the arm 55 be oscillated or rocked, its rocking movement will be transmitted to the rocking arm 52, and the amplitude of such rocking movement may be varied by adjusting the connector 57 in the slots of the two arms as indicated in Fig. 1.

In the present instance of the invention, 110 the arm 55 is actuated from the lay through a strap 59 connected at 60 to the lower end of the arm 55 and at its opposite end 61 to an arm 62 which may be secured to the lay through the intervention of a bracket 63. 115 The pawl 51 is normally under the influence of a light spring 64 tending to hold the pawl in operative relation with the teeth of the ratchet.

Mounted on the fixed bracket 65, Fig. 2, 120 which may be conveniently secured to the dead shaft 49 is a holding pawl 66 normally held in locking engagement with the ratchet teeth by a spring 66*. The backward movement of the lay acts through the strap 125 59 to give the pawl 51 its active stroke, and spring 52* returns the pawl through its idle stroke to its original set position defined by a stop or pin 53*.

Secured to or formed as a part of the 130

ratchet wheel 50 is a trip lug 69 which may be conveniently formed on a disk 70 secured to or formed as a part of the ratchet wheel 50.

- 5 Adjustably connected to the disk 70 and consequently to the ratchet wheel is the detent controlling cam 71 having a cut-out or recessed portion 72, best shown in Fig. 2, and upon the cam 71 travels the roller 73 carried by the arm 38. When the roller 73 is traveling along the main periphery of the cam 71, the detent will be held in frontward position, and when the recess 72 of the cam comes opposite the roller 73 during the step by step movement of the ratchet, the detent will move to a rearward position under the stress of a spring 67, one end being connected to the fixed arm 68 and the other to the detent, as shown.
- 10 From the construction described it will be apparent that the trip lug 69 and the cam 70 will be moved step by step through the action of the ratchet, and when the trip lug 69 rises beneath the detent it engages a lug 74 to thereby lift the detent from holding engagement with the feeler, whereupon the feeler is free to move to its feeling position under control of the feeler spring 27. When the depressed portion 72 of the cam 71 presents itself to the roller 73, the detent will be moved to its rearward position, as indicated in Fig. 2, so that should the feeler be moved frontwardly by a working supply of filling on a detecting beat, it will be engaged by the active end of the detent and held until as the roller 73 moves out of the depression 72 the detent will withdraw the feeler further frontwardly beyond the reach of the filling on detecting beats.
- 15

The length of the periods of activity of the feeler depend upon the relation of the trip lug 69 to the cam 71 in their sequential order of operation, and in order to enable the feeler to have longer or shorter periods of activity in accordance with the character of filling being employed, the cam 71 is secured adjustably to the ratchet, so that the sequential order of operation of the trip lug and the cam may be altered or arranged to provide for longer or shorter periods of activity of the feeler.

In the present instance, the cam 71, as best shown by Fig. 2, is provided with a slot 75 which is made concentric with the axis of rotation of the ratchet wheel, the trip lug and the cam, and the latter is adjustably secured in place relative to the trip lug by a bolt or screw 76, see dotted lines, Fig. 2.

From the construction described as one good form of the invention, it will be apparent that the detent controlling cam 71 may be adjusted relative to the trip lug 69 so that the withdrawing action of the cam

71 may take place and withdraw the feeler to its inoperative position after one, two, three or any number of detecting beats following the release of the feeler to its feeling position.

70 It will also be apparent that owing to the varied amplitude of movement that may be imparted to the active pawl 51, the frequency of the active periods of the feeler may be changed to agree with the character 75 of the filling employed. While the mechanical details for carrying the present invention into effect are simple and effective, but within the true scope of the invention, it is to be understood that the details may be varied.

80 When weaving with fine filling, the frequency of the release of the feeler to its periods of activity may be made to occur at longer intervals than when weaving with a coarser filling, and where the filling carrier is more rapidly depleted the parts may be so arranged that the feeler may be released to its periods of activity more frequently in accordance with the requirements 85 of the particular filling being used.

85 Should the feeler be in its feeling position on a detecting beat, as indicated in Fig. 1, and be moved frontwardly by a working supply of filling, it will be engaged by the detent provided the detent has been permitted to move to its rearward engaging position by the recess 72 of the cam, and on movement of the cam, the detent will withdraw the feeler to a position beyond the reach of the filling. Should the feeler, however, meet the filling at a time when that opposite the feeler is approaching a condition of substantial exhaustion, it will not be moved far enough to be engaged by the 90 detent and will remain in action until, when the filling is substantially exhausted, replenishment of filling will be called.

95 100 What is claimed is:

105 110 1 In a feeler mechanism for looms, the combination of a feeler, means for moving the feeler to an inoperative position beyond the reach of the filling on detecting beats, a trip for releasing the feeler at intervals that it may have periods of activity and inactivity during weaving with the same supply of filling in the shuttle, and means for changing the relation between the feeler moving means and feeler trip that the periods of activity of the feeler may be 115 made longer or shorter.

120 125 2 In a feeler mechanism for looms, the combination of a feeler, means for moving the feeler to an inoperative position beyond the reach of the filling on detecting beats, a trip for releasing the feeler at intervals that it may have periods of activity and inactivity during weaving with the same supply of filling in the shuttle, a common actuator for the said means and trip, and 130

means for varying the relation of the said means and trip that the feeler may have longer or shorter periods of activity.

3. In an intermittent feeler mechanism for looms, the combination of a feeler to detect the condition of the filling in the shuttle and effect replenishment when the filling is substantially exhausted, means for holding the feeler in an inoperative position during its periods of inactivity, mechanism for freeing the feeler from said holding means at intervals that the feeler may have periods of activity and inactivity during weaving with the same supply of filling in the shuttle, and means for making the active periods of the feeler longer or shorter at will relative to the inactive periods that the feeler may repeat its detecting function any desired number of 20 times during its active periods.

4. In an intermittent feeler mechanism for looms, the combination of a feeler, a device to hold the feeler in a forward retracted position, a trip for freeing the feeler at intervals that the feeler may have periods of activity and inactivity during weaving with the same supply of filling in the shuttle, an actuator for operating the trip, and means for varying the relation between the holding device and trip that the feeler may have longer or shorter periods of activity.

5. In a feeler mechanism for looms, the combination of a feeler having periods of activity and inactivity with respect to the filling in the shuttle, means to engage the feeler and hold it in retracted position, means acting at intervals to release the feeler that it may move to feeling position, means acting through the feeler engaging 40 means to withdraw the feeler to a position beyond the reach of the filling, and connections between the feeler releasing means and feeler withdrawing means for varying the duration of the periods of activity of the feeler.

6. In an intermittent feeler mechanism for looms, the combination of a feeler having periods of activity and inactivity with the same supply of filling in the shuttle, means for holding the feeler in a position beyond the reach of the filling during its period of inactivity, a trip for freeing the feeler to its periods of activity, and means for varying the duration of the periods of 55 feeler activity relative to the periods of inactivity and the frequency of their occurrence.

7. In an intermittent feeler mechanism for looms, the combination of a feeler, a 60 detent for moving the feeler into an inoperative position beyond the reach of the filling on detecting beats, a trip for tripping the detent at intervals that the feeler may have periods of activity and inactivity during weaving with the same supply of filling

in the shuttle, and a step-by-step device actuated from the lay for moving and tripping the detent.

8. In an intermittent feeler mechanism for looms the combination of a feeler, a detent and an actuating device therefor to withdraw the feeler to an inoperative position beyond the reach of the filling on detecting beats, a trip for freeing the feeler at intervals that it may have periods of 70 activity and inactivity with the same supply of filling in the shuttle, means for changing the relation of the actuating device and trip that the feeler may have longer or shorter periods of activity.

9. In an intermittent feeler mechanism for looms, the combination of a feeler, means for moving the feeler to a forward inoperative position and holding it for periods of inactivity, a trip for freeing the feeler from said means at intervals, and means for changing the operative relation between said means and trip that the active periods of the feeler may be made longer or shorter.

10. An intermittent feeler mechanism for looms, comprising, in combination, a feeler, a detent for holding the feeler in an inoperative position for periods of time and freeing it at intervals that it may have periods of activity and inactivity during weaving with the same supply of filling in the shuttle, controlling means for the detent including a ratchet wheel, a pawl, an arm carrying the pawl, an actuator for said arm, and connections between the arm and actuator for varying the active stroke of the pawl and the frequency of active periods of the feeler.

11. An intermittent feeler mechanism for looms, comprising, in combination, a feeler, a detent for controlling the feeler, a trip for 105 freeing the feeler from the detent, a cam for moving the detent forwardly to place the feeler beyond the reach of the filling, and means for adjusting the relation of the cam and trip.

12. In a feeler mechanism for looms, the combination of a feeler, a detent for controlling the position of the feeler, a trip for freeing the feeler from the detent at intervals that the feeler may have periods of activity and inactivity during weaving with the same supply of filling in the shuttle, means acting through the detent to move the feeler to a forward inactive position, and devices between said means and trip for changing their relation that the feeler may remain in performance of its feeling function for a number of detecting beats during its active periods.

13. In a feeler mechanism for looms, the combination of a feeler, a detent for engaging a part connected to the feeler, means for moving the detent forwardly, a trip for freeing the feeler from the detent at intervals that the feeler may have periods of ac- 125

tivity and inactivity during weaving with the same supply of filling in the shuttle, means for changing the intervals of operation of said means and trip that the periods of activity of the feeler may be made longer or shorter.

14. In a feeler mechanism for looms, the combination of a feeler, a detent for engaging a part connected to the feeler, means for moving the detent frontwardly, a trip for freeing the feeler from the detent at intervals that the feeler may have periods of activity and inactivity during weaving with the same supply of filling in the shuttle, means for changing the intervals of operation of said means and trip that the periods of activity of the feeler may be made longer or shorter, and means for changing the frequency of the active periods of the feeler.

15. In a feeler mechanism for looms, the combination of a feeler, a detent for determining the position of the feeler, and controlling means for the detent comprising a cam for moving the detent and feeler

frontwardly, a trip for freeing the feeler from the detent at intervals, means for adjusting the relative positions of the cam and trip, and a ratchet operated mechanism for actuating the cam and trip in their adjusted relation.

16. In a feeler mechanism for looms, the combination of a feeler, a detent for controlling the feeler that it may have periods of activity and inactivity during weaving with the same supply of filling in the shuttle, a ratchet mechanism for controlling the detent comprising a ratchet wheel, a rocking arm carrying a pawl at one end, a second rocking arm constituting an actuator for the pawl carrying arm, connections between the second rocking arm and the lay, and adjustable connections between the two arms that the amplitude of movement of the pawl carrying arm may be changed.

In testimony whereof, I have signed my name to this specification.

HARRY A. DAVIS.
